UNITED STATES PATENT OFFICE.

MALCOLM L. ORD, OF INDEPENDENCE, KANSAS.

AUTOMATIC PHONOGRAPH.

Application filed August 4, 1920, Serial No. 401,105. Renewed January 19, 1922. Serial No. 530,494.

To all whom it may concern:

Be it known that I, MALCOLM L. ORD, a citizen of the United States, residing at Independence, county of Montgomery, State 5 of Kansas, have invented a new and useful Automatic Phonograph, of which the following is a specification.

The object of my invention is to provide novel means for successively placing a series 10 of disk type records on suitable turntables automatically revolved into position for receiving them; to provide novel means for successively removing the records from the turntables after they have been played once 15 or after having been automatically repeated any number of predetermined times; to provide novel rotary means for supporting a plurality of turntables and rotating same to the appropriate position for receiving, for 20 playing and for removing the records during the automatic operation of the phonograph; to provide an apparatus to hold a series of either ten or twelve inch disk records and adapted to play any of the 25 standard types equally as well, such apparatus also adapted to eject the records it supports, one at a time, upon a turn table positioned to receive the same; to provide novel means for putting on and removing 30 the records by mechanisms that come in contact only with the portion of the records near their outer edge so as to obviate possibility of injury to the sound grooved portion of the record; to provide novel means 35 for automatically repeating any one or all of the records before proceeding to the playing of the successive record, for any predetermined number of repetitions; and to provide an improved tone arm and improved 40 reproducing mechanism, including novel means for regulating the feeding operation of the reproducer while playing a record and for returning same to its starting position, after a record has been played or 45 repeated; it is also an object of my invention to provide a tone arm and throat without sharp bends or flexible elbows which might tend to reduce the volume of the tone or break up the sound waves. It is further 50 my object to provide a comparatively simple mechanism for performing the numerous and complex operations which are automatically performed by this machine; and to provide an apparatus so as to permit 55 of its being mounted in a cabinet of suitable size and design for home use, and

capable of being successfully operated by any one. It is further an object of my invention to provide a phonograph which is electrically automatic in all of the operations 60 of putting on, playing and taking off of a series of records of varying diameters, and repeating any of the desired record or records in the series as many times as predetermined by the operator. It is also an 65 object of my invention to provide a mechanism which will operate with practically no noise, so that no undesirable sound will be heard during the changing or repeating of records. It is further an object of my invention to provide electrical operation 70 throughout to obviate the cranking necessitated by spring actuated operation. It is further an object of my invention to provide novel means adapted to be readily 75 attached to the records whereby when the end of the record tone groove is reached by the needle an electric circuit will be closed through said means to cause the machine to function and complete the operation 80 of changing or repeating the records.

I attain these and other objects of my invention by the mechanism disclosed in the accompanying drawings, in which:—

Figure 1 is a top plan, showing the upper turntable removed to allow view of mechanism beneath;

Fig. 2 is a vertical longitudinal sectional view on line 2—2 of Fig. 1;

Fig. 3 is a vertical cross section on line 90 3—3 of Fig. 1;

Fig. 4 is a similar fragmentary cross-section showing reproducer assembly in elevated position;

Fig. 5 is a vertical cross section on line 95 5—5 of Fig. 1;

Fig. 6 is a sectional view on line 6—6 of Fig. 1;

Fig. 7 is an enlarged fragmentary cross-section on line 7—7 of Fig. 1, showing reproducer and telescopic tone tube extended 100 to end of record;

Fig. 8 is a horizontal longitudinal sectional view approximately on line 8—8 of Fig. 2;

Fig. 9 is a detail view showing lock 16 for retaining turntables in bearing 7 when same are in inverted position and showing the springs on shafts 14 which make contact with metal plate 75;

Fig. 10 is a detail view of metal plate 110 as applied to record;

Fig. 11 is a cross sectional view on line 11-11 of Fig. 10;

Fig. 12 is a perspective view of record-holding and ejecting carriage 96;

Fig. 13 is a view of toothed rack on solenoid core;

Fig. 14 is a detail perspective view of sliding table used for setting record repeat;

Fig. 15 is a detail view of ratchet, gear 10 and hub 163^b and 163;

Fig. 16 is a diagrammatic view showing the electric circuits used to operate the mechanism.

Fig. 17 is a detail view of mechanism 15 used in causing record tables to advance toward turn-tables; and

Fig. 18 is a detail view of members 88, 86 and 87.

Fig. 19 is a detail sectional view showing 20 return spring 53^a on shaft 49 and adjacent parts;

Fig. 20 is a detail elevational view of a suitable electric motor for replacing solenoids 56 and 166, mentioned on page 26, 25 lines 7-14.

Referring to the accompanying drawings, in which similar numerals and letters refer to similar parts throughout the several views, I provide a suitable cabinet 1 as shown in Figs. 1 and 2, in which is contained an aluminum sub-base 2 to which all supports of the mechanism are either integral or bolted thereon and which is mounted on rubber pedestals 3 to insulate against sound board effect of cabinet during playing. Mounted on sub-base 2 I provide central supports 4 as shown in Fig. 4, on which is mounted a stationary ring 10. Rotatably mounted on ring 10 I provide an annular bearing 7 on which the turntables 11, of which there are four, are mounted. I further provide an annular bearing 8 rotatably mounted on ring 10 and supporting solenoid coil 86 whose core 87 is in varying active engagement with stops 89 mounted on bearing 7 for the purpose of rotating this bearing at time of record change. I further provide that members 7 and 8 are both ball bearing elements; bearing 8 rotates parallel to and independent of bearing 7 except at desired intervals when core 87 operatively engages and actuates the latter.

I provide record-holding turntables 11, 55 shown in Figs. 1, 2, 3 and 7, of which there are four, mounted at right angles to one another on the outer circumference of the annular bearing 7. Each of the turntables 11 is provided with an annular recess 12 60 suitably positioned to permit of the entrance of the ends of the toothed record-advancing racks 128 to engage the records for removal of the same when they are of ten-inch diameter and when such a series is being played. I provide on each of the turn-

tables 11 suitable miter gears 13, as shown in Fig. 2, acting as hubs for the turntables 11. Each turntable 11 is provided with central shafts or record-centering pins 14 projecting above the turntables for locating 70 the records thereon, and projecting below and through the miter gears 13 to engage in corresponding openings or journals 15 in the annular bearing 7; the centering pins are made pointed to allow records to be easily slipped on and off of the turntables. I provide permanent locks 16 adapted to engage a grooved portion of the turntable shafts 14 to prevent said turntables 11 from dropping off when they are rotated to their lowermost position, at which point they are inverted.

I provide a metal horn throat 5, as shown in Fig. 4, which terminates at and concentrically fastens on ring 10 connecting with wooden amplifying sound chamber 6 through ring 10, said ring 10 constituting an actual part of the amplifying sound chamber of which it is an extension. Hinged to horn throat 5 at its small end, by hinge 22, is a base 24, as shown in Figs. 3 and 4, of insulated material, on which is mounted an adjustable tone arm 26 into which telescopes the floating tone tube 27, which latter member is supported on reproducer carriage 66. I provide a suitable cam 17 on bearing 8 for raising hinged base 24, by means of a plunger pin 18 slidably mounted in a suitable support and bearing 19, shown in Figs. 3 and 4, the other end of the plunger pin 18 being in operative contact engagement with a bell-crank or elbow lever 20, which in turn is connected by a link 23 to an insulated lever 21 which engages the hinged base 24 in such a manner as to raise and lower same.

Mounted on hinged base 24, in spaced relation from adjustable tone arm 26, I provide reproducer carriage supporting arms 25 adapted to support the reproducer carriage 66 while same is passing over record during playing and returning it to starting point of next record; the raising of arms 25, as shown in Fig. 4, cause carriage 66, to which reproducer is fastened, to recede by gravity into adjustable tone arm 26, returning the reproducer 65 from extended position, as shown in Fig. 7, to receded position, shown in Fig. 4.

In order that the reproducer 65 may be fed along over the record automatically, so as to relieve the tone thread of the record of undue wear, I provide a lead screw 28 having one hundred threads per inch on its 125 threaded portion to correspond with the number of threads per inch on most disk records (such as Victor or Columbia which have one hundred tone threads per inch). Lead screw 28 is mounted on suitable bear-

ings 29. Permanently mounted on the non-threaded end of lead screw 28, as shown in Figs. 1, 3 and 4, I provide a cog wheel or gear 30 in one-to-one ratio with its driving gear 35. Spaced from gear 30 and also permanently mounted on shaft 28 I provide a one-and-one-half to one gear 31, which is utilized to make the lead screw adjustable for the operation of the machine with Edison or similar records having one hundred and fifty threads to the inch. Alternately meshing with gear 30, according to gear ratio needed on lead screw, I provide a suitable gear 35 for driving the lead screw 28 at the one-to-one speed; and alternately meshing with gear 31 to allow for ratio change, I provide a gear 36 for driving the lead screw 28 at a one to one-and-one-half speed. I provide a collar hub 37 permanently supporting gears 35 and 36, said hub being keyed to a shaft 33 by a suitable sliding key-way 38 to allow for the sliding of collar hub 37 on shaft 33 during the change of gears. Shaft 33 is mounted on suitable bearings 34 and on its other end carries a suitable miter gear 32 which is adapted to mesh, in a ratio of one to one with the gears 13 which form the hubs of the turn-tables 11, and by which, through the train of gears above described, the lead screw 28 is driven. I provide a shift lever 39 engaging collar hub 37 and adapted to operate same for changing the mesh of gears 35 and 36 with the lead screw gears 30 and 31, and thus change the speed of the lead screw. Shift lever 39 is pivoted on a suitable bracket 40.

To operate the turntables 11 when in playing position, I provide an electric motor 41, shown in Figs. 1 and 3, on which is mounted a friction wheel 42 carried by the extended upper end of the motor shaft. The outer edge of the friction wheel 42 engages the outer edge of recesses 12 of the turntables 11 as same come into playing position. I provide a governor of conventional type for controlling the motor speed, this governor being mounted by spiral gears on motor shaft of motor 41, and being regulated by suitable adjusting screw 47. I provide a spring controlled plunger 44 bearing against the motor 41 for the purpose of causing the friction wheel 42 to press against the edges of the turntable recesses 12, thereby engaging same to cause a revolution of eighty revolutions per minute plus or minus any reasonable variation in speed to suit the tempo of the record being played; this being done by regulation of governor 43. To limit or control the tension of the friction wheel 42 against the turntables 11 as they come in contact with it, I provide an adjustable stop 45 which engages the motor 41. The motor 41 is mounted on a pivoted bracket 46, the bracket 46 being pivoted so as to allow the necessary tilting forward of the motor 41 and the friction wheel 42 so as to bring the latter into engagement with the edge of the turntable recesses 12. To provide smooth and even operation of the turntables 11 I have placed an armature 203 in motor 41 of very large diameter and unusual weight which acts as a fly-wheel to create steady revolution of motor shaft and thereby overcome any slight speed variations due to a possible fluctuation in the electric current. For the purpose of rotating bearing 7 (which carries the turntables 11) and the cam 17 for lifting the hinged base 24 after a record has been played, I provide a solenoid coil 56 mounted on a suitable base support 57 and magnetically controlling the steel solenoid core 53 which on its extended lateral side supports a rack of limited slidable motion 52 which rack 52, together with the steel core 53, is normally held in elevated position by a suitable spiral or clock spring 53^a mounted on shaft 49. When solenoid 56 is energized it pulls armature 53 down all the way until it hits the end of lever 62, which breaks the circuit to the solenoid 56 and spring 53^a is fully wound. As soon as the circuit is broken the spring simply acts to reverse the rotation of the shaft 49, which restores the armature 53 to its original position. The toothed rack 52 engages a spur gear 51 which is permanently mounted on the inner end of the driving shaft 49 which shaft is mounted on bearings 50; and on its outer end carries a permanently mounted spur gear 48 which meshes with gear 9 to revolve bearing 8 when a change of records or a repeat is in sequence. I provide a spring 55, as shown in Fig. 13, 105 at the upper end of the steel core 53 to relieve tension between slidable rack 52 and spur gear 51 when the core 53 is pulled slightly past the stopping point of rack 52 for the purpose of resetting the L-shaped 110 armature 60. The resetting of this armature breaks the circuit through the solenoid coil 56 allowing spring 53^a to return the mechanism actuated by solenoid 56, to its original position. Steel core 53 is slidably mounted in U-shaped guide 54 which serves to keep rack 52 in mesh with gear 51.

I provide a magnetic switch 58, shown in Figs. 1, 3, 4 and 16, to control the current for solenoid 56. This device comprises a switch magnet 59 (magnetized when the steel spring brush 74 carried by the reproducer 65 comes in contact with a suitable metal plate 75, as shown in Figs. 10 and 16, which has been attached to each record and which extends from the center of the record to the end of the record groove); an L-shaped switch armature 60 mounted on a pivot 61 and provided with a hook 64 which is adapted to hold a movable circuit contact lever 62 130

out of contact with a stationary circuit contact 63 during the playing of the record.

I provide a suitable reproducer or sound box 65 shown in Figs. 1, 2 and 3, mounted on a suitable arm 67 as its extension. The end of arm 67 is mounted by means of pivot 68 to a suitable carriage 66 which supports the reproducer 65 and also the telescopic tone tube 27. As the reproducer is pivotally supported at 68 relative to the reproducer carriage 66, free vertical and horizontal movement is permitted sufficient to overcome any irregularity in the record or turntable, without interfering with the forward movement 10 of lead screw 28 which is positive and non-flexible. I provide a suitable L-shaped insulated lever 69 mounted on carriage 66 and having its lower end in operative engagement with the lead screw 28 by means of a 15 semi-floating half nut 72 threaded to correspond with the thread of the lead screw (one hundred threads per inch). The arm 69 is held in engagement with the lead screw 28 when tone arm is down in playing 20 position by a suitable spring 71. It is within the contemplation of my invention to employ a suitable weight in lieu of the spring 71. The carriage 66 is movably mounted on rollers 73 which ride on supporting arms 25.

The plates 75, as shown in Figs. 10 and 11, are used on the records to provide a conduit for the electrical current from the record centering shaft 14 to the end of the record 30 grooves when contact is made by brush 74 as reproducer comes to end of record. I provide springs 76, as shown in Fig. 9, passing through shafts 14 which make positive metallic contact between the metal plates 75, 35 Figs. 10 and 11, on the record and shafts 14. In consequence of the fact that the metal plate 75 extends to the end of the record groove, an immediate changing of records is effected as soon as the playing is 40 finished and similarly when a record is to be repeated, the repeating is done without delay.

The turntables 11 are locked in position for playing by means of an automatic stop shaft 77, as shown in Figs. 3, 4 and 7, which is adapted to engage in recesses 78 of bearing 7. These recesses 78 are disposed in the same relative position on bearing 7 as the turntable. Shaft 77 is mounted on suitable 50 bearing 79 and is loosely mounted so as to permit of longitudinal and limited clockwise rotary motion. I provide a suitable cam 80 on bearing 8 which is adapted to engage the arm 81 (as shown in Figs. 1 and 6) on shaft 55 77 and thereby to cause shaft 77 to move rearwardly out of engagement with recesses 78 in bearing 7 to permit the latter to rotate and move the turntable into the next position. The action of cam 80 takes place on 60 the rotation of bearing 8 before the core 65

87 engages with ratchet stops 89; this releases the lock shaft 77 before the rotation of bearing 7 commences. During the first part of the revolution before bearing 7 starts to revolve, cam 17 has raised reproducer 65 70 off of the record, thereby clearing the record turntables which are then about to turn into new position; this action eliminates any danger of needle dragging across record. I provide a spring 82 which keeps endwise 75 tension on shaft 77 to insure the latter entering the recesses 78 at the proper time. I also provide a spring 83 allowing a limited clockwise rotation of shaft 77 when cam 80 passes arm 81 on the return revolution. This action allows the shaft 77 to remain in position in recess 78 by depressing arm 81 allowing clockwise rotation sufficient to clear cam 80 on the return movement of bearing 8; which latter bearing rotates approximately 85 one-third of a revolution during each change and repeat of record. The reason bearing 8 revolves farther than bearing 7 is to allow for the release of lock shaft 77 before core 87 engages stop 89; after this has been 90 released both bearings revolve one-quarter of a revolution. At the end of the revolution of bearing 8 the mechanism is immediately returned to its former position by means of a spring 53^a, as shown in Fig. 1, 95 when movable circuit lever 62 is returned to hook 64 by the downward motion of field core 63. I provide a stop 84 adapted to prohibit anti-clockwise motion of shaft 77 when arm 81 comes in contact with cam 80; 100 this stop is engaged by arm 85 (as shown in Fig. 1) permanently mounted on shaft 77.

I also provide means for permitting of the repeating of playing of records any desired number of times. Bearing 7 which carries the turntables 11 is provided with ratchet stops 89 positioned opposite the turntable shafts 14 on the side of the bearing 7 in proximity to bearing 8. Mounted on bearing 8 I provide a small solenoid coil 86, as shown in Fig. 4, having a slidable steel core 87 which is normally pressed outwardly against the lateral surface of bearing 7, by a suitable spring 88 contained within the core 87. The core 87 when in its normal outward position is in position to engage the ratchet stops 89 on bearing 7 and thus to rotate that member and the turntables 11 simultaneously with the rotation of bearing 8. When the record is to be repeated such rotation is not desired in bearing 7, as the turntable supporting the record to be repeated must remain stationary. To control the current through the solenoid 86, I provide a roller binding post which is adapted to make contact with a suitable spring contact 92 during a part of the revolution of bearing 8, and thus to complete a circuit through the solenoid 86 and draw the steel 115 120 125 130

core 87 into the solenoid and out of engagement with ratchet stop 89, allowing bearing 8 to rotate independently of bearing 7, as will be seen by referring to Figs. 4 and 7.

I provide a suitable brake or ratchet stop spring 95, shown in Fig. 2, in operative engagement with bearing 7 to prevent that member from revolving in a reverse direction when core 87 is drawn out of engagement with it into solenoid 86 during the repeating of a record. This brake functions as a safety device during the repeating of records.

15 In order to operate the record carriages 96 and 125, as shown in Figs. 1 and 2, after revolving the record turntables 11 I provide a switch 93 adapted to be closed by insulated blocks 94 which are mounted 20 on bearing 7 and positioned in the same relative position as the turntable shaft 14. Switch 93 controls the current through switch magnet 171 which in turn controls the current through solenoid 166.

25 In order to provide means for holding and placing of selected records on the turntables 11 and to provide for utilizing either a series of ten inch or a series of twelve inch records or any other series of disk records 30 within these limits, I provide a suitable record-holding and ejecting carriage 96, as shown in Figs. 1, 2, 5 and 12, which is supported by rollers 97 resting on supports 98 which form the tracks for same. I provide

35 side bars 101, shown in Fig. 12, of carriage 96 which are movable only longitudinally and in groups of three as the framework of the carriage itself. These side bars 101 are provided with transverse slots 101^a to 40 receive the toothed rack slide projections which are integral with bars 102. Bars 102 support the toothed record holding and advancing racks 99 and 100. Racks 99, operating simultaneously in groups of three, 45 are slideable longitudinally to advance records in and from the carriage; and are also receivable laterally to pass back of the records in the carriage one tooth after having advanced them. During this last operation 50 the record at the end near the turntable has been ejected from the carriage 96 onto shaft 14 of the turntable parallel to record. All other records in carriage 96 have been advanced one tooth bringing the next record 55 to be played to the end of the carriage ready to be ejected. Toothed ratchet-holding stop racks 100, also operating simultaneously as groups of three, are movable only laterally, and operate to hold the record stationary when racks 99 move backward after having advanced the records one tooth. I provide suitable flat steel springs 114 which exert tension on advancing racks 99 to hold 60 them against the edge of the record and to allow the racks to recede when passing be-

hind them. The action of springs 114 is limited by pins 116 which project into slots 117 provided in the ends of racks 99 to limit both the longitudinal and lateral movement of these racks. I also provide similar suitable springs 115 bearing against toothed ratchet holding stop racks 100; and similar pins 118 extending into slots 119 in the ends of these racks, whereby pins 118 limit the receding or lateral movement of racks 100. 70 I provide levers 120 pivoted on bars 102 by means of pins 122 which act as fulcrums for levers 120. Levers 120 have slotted ends which are engaged by pins 121 mounted on the toothed record advancing racks 99, 80 whereby the latter are actuated to produce the longitudinal movement for the purpose of moving the records forward and also allowing free receding movement in the slots at the ends of the levers 120. These levers 85 120 are actuated by the spaced stops 123 and 124. These stops actuate lever 120 on each forward and return movement of carriage 96 and in turn move racks forward to the end of carriage, ejecting a record and advancing the rest on the forward movement and receding behind all of the records on the return; this places the rack 99 in position to repeat the operation. It is understood that all three sets of racks 99 and 100 95 are actuated simultaneously to advance records evenly and at the same time support them in their predetermined position.

In order to produce a mechanism for quickly converting the carriage to a size 100 adapted for holding records of various sizes, I provide small gears 104 shown in Figs. 5 and 12, which mesh with toothed rack slides 103 of bars 102 and which are mounted on shafts 105, which in turn are supported in 105 bearings 106. I provide spur gears 107 on the ends of shafts 105 which are utilized to rotate the shafts and the gears 104 carried by them. I provide a large gear segment 108 at the end of the record-holding carriage opposite to the one from which the records are ejected, and arranged to mesh with spur gear 107. Segment 108 is provided with a suitable handle 109, whereby 110 the segment may be manually operated to set the carriage 96 for a particular size of record. This handle 109 causes gear 108 to rotate equally all gears 104 which causes the bars 102 working in groups of three to expand or contract to receive any series of records from 9½ to 12 inches in diameter. In order to provide means for locking segment 108 in any desired adjusted position, I provide a ratchet lock mounted on releasing rod 110, which engages with a suitable 115 segment ratchet 111 mounted on the end member of the carriage 96, the aforesaid ratchet being of like structure and equivalent in operation to the ratchet lock 141 shown at the other end of the machine and il- 120 125 130

lustrated in Fig. 5. The segment 108 is supported in a suitable bearing 113, mounted on the end member of carriage 96.

In order to provide means for holding and receiving the records from the turn tables 11 after the records have been played, I provide a suitable record-receiving carriage 125, similar to carriage 96 except that the record-holding and advancing racks 128 and 129 are arranged to take the record from the turntable instead of ejecting it onto the turntable and the expanding segment 137 is placed on the end member of carriage 125 at the opposite end. This carriage is supported on rollers 126 resting on supports 127 which form tracks for same. I provide side bars 130 of carriage 125 which are movable only longitudinally and as a group of three forming the framework of the carriage. Side bars 130 are provided with transverse slots 130^a to receive toothed rack slide projections 132 which are integral with bars 131. Bars 131 support toothed record-holding and advancing racks 128 and 129. Racks 128 are slidable longitudinally to advance records in the carriage away from the turntable and are also recedable forward to pass one tooth in front of records held in carriage after being taken from turntable. Toothed racks 129 are movable only laterally, and operate to hold the records stationary when racks 128 move forward after having advanced the record one tooth away from the turntable. I provide suitable flat springs 143 which exert tension on toothed record advancing racks 128 to hold them against the edges of the records and to allow these racks to recede ahead of the records in the table to grasp the next record to be removed. The action of the springs 143 is limited by the pins 145 which project into slots 146 provided in the ends of racks 128 to limit both the longitudinal and lateral movement of these racks. I also provide suitable similar springs 144 bearing against racks 129; and I provide pins 147 extending into slots 148 in the end of racks 129, whereby pins 147 limit the lateral or receding movement of said racks. I provide levers 149 pivoted on bars 131 by means of pins 151 which act as fulcrums for levers 149. Levers 149 have slotted ends which are engaged by pins 150 mounted on racks 128 whereby the latter are actuated to produce the longitudinal movement for removing records from the turntable and advancing those removed on the receiving carriage 125. In order that the first teeth of racks 128 may pass behind the outer edge of a ten-inch record to allow its removal from the turntables 11 I have provided an annular recess 12 in turntables 11. As all twelve-inch records extend over the edge of the turntables 11 sufficiently to allow the teeth to grasp the record, no such provision is

made for the twelve-inch records. Levers 149 are actuated by spaced stops 152 and 153 to produce the longitudinal movement of the racks 128 to advance the records on the carriage and away from the turntables. In order to provide for the receiving of either ten or twelve inch records or of any other desired size between these limits, I have provided an expanding mechanism composed of small gears 133, as shown in Figs. 5 and 12 which mesh with toothed racks slides 132 of bars 131, and which are mounted on shafts 134 and which in turn are supported in bearings 135. I provide spur gears 136 on the ends of shafts 134 which function to rotate the shafts and the gears 133 carried by them. I provide a large gear segment 137 at the end of the record-holding carriage 125 positioned to mesh with spur gears 136. This segment rotates all three of the gears equally, by which action all three bars 131 are caused to expand or contract to receive any series of various sized records. Segment 137 is provided with a suitable handle 138 whereby the segment may be manually operated to adjust the carriage for the particular size of records which it is desired to remove from the turntable. I provide a means for locking segment 137 in any desired adjusted position, consisting of a ratchet lock 141 upon releasing rod 139, which engages with a suitable segment ratchet 140 mounted on the end member of carriage 125 opposite its receiving end. Segment 137 is supported on suitable bearing 142 mounted on the end member of carriage 125.

In order to provide for simultaneously advancing the record-containing carriages 96 and 125 toward the turntables 11 whereby the records are deposited and removed from the said turntables and returning same to their original positions whereby the advancing ratchet racks are re-set for the next shift, I have mounted on stationary lever bearing 154, as shown in Fig. 8, a central operating lever 155 to which is attached equi-distant from the center of lever 155, the connecting links 156 and 157 which connect lever 155 with carriages 96 and 125, respectively. To provide for the movement of central lever 155 I have provided a connecting rod 158 attached to end of lever 155 and whose opposite end engages with crank pin 159 on revolving crank arm 160. To provide support for crank arm 160 I have supported shaft 161 in bearing 162; the crank arm being mounted on shaft 161, as shown in Fig. 17, on one end and a loosely mounted spur-gear 163 with its attached ratchet pawl 163^a on the other end; this spur gear 163 is arranged to mesh with toothed rack 164. Permanently mounted on shaft 161 engaging ratchet pawl 163^a. I provide a ratchet hub 163^b to engage with pawl 163^a on gear 163.

so that same will rotate shaft 161 and arm 160 attached thereto, one complete revolution. This action is made possible when core 165 is drawn in to solenoid 166. The 5 ratchet allows the gear 163 to rotate back to starting position by means of spring 162 which actuates when end of core trips the movable contact lever 174, releasing the current through solenoid 166.

10 I provide a magnetic switch 170 to control the current for solenoid 166, which solenoid is the actuating member for revolving the gear 163 by means of its core 165 and attached rack 164. The magnetic switch comprises a switch magnet 171 (this magnet is magnetized when switch 93 is closed by insulated block 94 during the rotation of bearing 7); an L-shaped switch armature 172 mounted on the pivot 173 and provided with a hook 176 which is adapted to hold a movable circuit contact lever 174 out of contact with a stationary circuit contact 175 when the magnet 171 is not excited.

15 The solenoid 166 has a steel core 165 which carries a rack 164, this rack 164 is in mesh with gear 163. I provide a guide of U-shaped cross section 168 in which steel core 165 is slidably mounted to keep rack 164 in mesh with gear 163. Solenoid coil 166 is 20 mounted on a suitable base support 169. I provide a spring 167 on the outer end of core 165 and engaging with outer end of rack 164 to relieve tension on gear 163 when core 165 is drawn past the stopping point of 25 rack 164 at the time of restoring movable circuit contact lever 174 to hook on L-shaped armature 172.

30 In order to permit of the repeating of records for the desired predetermined number of times, I provide means for preventing the rotation of bearing 7 and turntables 11 after the playing of the record has been completed, allowing the hinged base 24 to elevate and return the reproducer 65 by 35 gravity to starting position on record groove. For determining in advance the number of times the record is to be repeated I provide a slide bar or table 177, shown in Figs. 1, 2 and 14, provided with dove-tailed grooves 179, there being one of these 40 grooves for each record in the rated capacity of carriage 96. Table 177 is slidably mounted on support 178 and its sliding action is controlled by ratchet rack 183 which 45 is engaged by pawl 184 supported on bracket 187 of carriage 96 and actuated against ratchet rack 183 by spring 185 and elevating stop 186. I provide movable toothed slides 180 mounted in grooves in 50 table 177 so that same may be drawn out of these grooves 179 manually by means of small knobs 182, a predetermined number of teeth to correspond with the number of 55 times the particular record which it represents is to be repeated. The capacity of 60

toothed slides 180 on table 177 is the same as the capacity of the record-holding carriage 96. In order to hold the movable toothed slides in the position set I provide 65 springs 181 operatively engaging each of the toothed slides 180. Mounted in front of traveling table 177 and parallel with movable toothed slides I provide a pronged 70 spring switch 194, each side of which carries an electric current of the circuit operating the solenoid coil 86. As sliding table 177 is advanced by the movement forward of carriage 96 these movable toothed slides which extend away from the table the required number of notches for repeating their respective records, enter into engagement with pronged switch 194. This closes the electric circuit between the pronged fingers of switch 194 during the time such record represented by the toothed slide in 75 engagement with switch 174, is being repeated.

80 It being necessary that movable toothed slides remain in position between the pronged fingers of switch 194, as shown in Figs. 2 and 14, as long as record is desired to be repeated, and then removed from position between pronged fingers after record has been repeated its predetermined number 85 of times, I provide spur gear 188 mounted on shaft 189 which in turn is supported on bearings 190. Gear 188 is adapted to mesh with movable toothed slides 180 as same are advanced by means of rack 183, which operation is caused by the forward motion of carriage 96. To provide for the rotation 90 of gear 188 I have provided on the opposite end of shaft 189 a ratchet gear 191, as shown in Fig. 3 which is actuated by a pawl lever 192 mounted on hinged base 24 when same is elevated and lowered. The action of pawl lever 192 is controlled by gravity. On the lowering of hinged base 24 pawl lever 192 engages with ratchet wheel 191, causing 95 same to rotate one tooth. As gear 191 and spur gear 188 are permanently mounted on shaft 189, such rotation causes movable toothed slide 180 to recede into dove-tailed groove 179, to the extent of one tooth. Electric switch 194 being mounted close to sliding table 177, continues to be closed as long 100 as any movable toothed slide extends therein so that it is necessary for tone arm on hinged base 24 to raise and lower the predetermined 105 number of times set for record repeat in order to cause any extended movable toothed slide to recede completely away from between prongs of electric switch 194. As 110 long as switch 194 is closed by any of the movable slides 180, the core of solenoid 86 remains withdrawn from engagement with ratchet stops 89 on bearing 7, allowing bearing 8 which raises hinged base 24 to revolve 115 independent of bearing 7, allowing the turntables to be unchanged. Binding posts 195 120

125

130

and 196 carry the current to both prongs of the switch 194.

In order to control the electric current which operates the various coils and motor as shown in Fig. 16, I provide binding posts 197 and 198 which receive the main electric current from its source and from which leads are taken to operate the entire apparatus. It being necessary to operate turntable 10 motor 41 at a voltage pressure of 110 volts, a circuit is taken directly from posts 197 and 198 and controlled by motor switch 199 mounted conveniently in the cabinet; the motor 41 is necessary to cause rotation of 15 the turntables as same come into playing position and operates no other part of the mechanism. As the magnets and solenoids used in the operation of the mechanism are to be operated on a six-volt current to prevent 20 electric shock of operator (due to current passing through metallic parts of machine), I provide a transformer 201 to reduce the 110-volt circuit to one of six volts. I may if desired provide a suitable condenser 25 coil 202 whose action is to prohibit any arcing of current at contact points. To control circuit between binding post 197 and 198, and transformer 201, I provide a conventional electric switch 200.

30 The operation of the electric circuits, as shown in Fig. 16, is as follows: The closing of switch 199 starts rotation of turntable which is elevated in playing position. The closing of switch 200 introduces main 110-volt current into transformer 201. The current leaves transformer 201 at six volts through bus-bars A and B, which supply current through the various coils operating the machine from this transformed current.

40 When metal spring brush 74 carried by reproducer 65, comes in contact with metal plate 75 carried by the record which has finished playing, it closes the electric circuit which starts where the current is tapped from main bus-bar B, at C, entering switch magnet 59 and leaving same at D, following wire E to binding post placed on any metal part of the machine excepting the insulated hinged base 24 (shown in Figs. 3 and 4) which is insulated from the rest of the machine in order to separately carry the current to the reproducer brush 74. This grounds the circuit to all metal parts except the tone arm assembly, allowing it to follow 50 to the turntable shafts 14 where metallic contact is made with metal strip 75 on record, through spring brush 74 and reproducer carriage 66 (shown in Fig. 4) to wire F, completing circuit at G with main bus-bar A.

The closing of the above-described circuit energizes switch magnet 59 which attracts L-shaped magnet 60, causing hook 64 to release movable circuit contact lever 62, 55 which falls in contact with stationary cir-

cuit contact 63. This action closes the circuit, energizing solenoid 56. This circuit starts at H where current is tapped from main bus-bar B, entering solenoid 56 at I and leaving same at J, where it is led to movable circuit contact lever 62 by wire K through stationary contact 63; completing circuit through wire L joining bus-bar A at M.

As shown on Fig. 1, the energizing of 75 solenoid 56 causes steel core 53 to recede within the solenoid, in turn causing toothed rack 52 to revolve gear 51 and gear 48 mounted on shaft 49. The revolving of gear 48, which is in mesh with gear 9 mounted on bearing 8 causes bearing 8 to revolve. The revolving of bearing 8 by means of description heretofore given raises the tone arm and revolves bearing 7, bringing the new turntable with the next record into playing 85 position; and returning reproducer by gravity to the starting point of the record just brought into position for playing.

After the rotatable bearing 7 has revolved through one-fourth of its arc (that is 90° 90 approximately), insulated block 94 compresses contact points on switch 93 which completes the circuit to magnetic switch 170. As shown in Fig. 16, this circuit receives current from bus-bar B at N and entering switch magnet by wire O at P, leaving same at Q and following wire R to switch 93, through this switch by wire S to main bus-bar A at T. The closing of this circuit excites coil 171 and attracts armature 172, thus causing hook 176 on armature 172 to release movable circuit contact lever 174, which drops in contact with stationary circuit contact 175. The dropping of this contact completes the circuit through solenoid coil 166, by receiving current from bus-bar B at U, entering solenoid at V and leaving same at W through wire X to movable contact lever 174 through stationary contact lever 175 and wire Y, completing circuit 100 with bus-bar A at Z.

The inward movement of the steel cores in solenoids 56 and 166 causes these cores on their extreme inward motion to come in contact with and raise movable contact arms 62 and 174, causing them to break contact with stationary circuit arm 175 and catch in the hooks of L-shaped armatures 60 and 172 which hold same out of contact; this opens the circuits controlling the solenoid coils, allowing them to return to normal position by means of springs 53^a (see Fig. 19) and 163^a (see Fig. 15) ready for a repetition of the current action when next record is to be changed.

Magnetic switches 58 and 170 act primarily as impulse switches to throw into operation the permanent switches at movable circuit arm levers 62 and 175. This is necessary because the closing of contact between 120

brush on reproducer 65 and plate 75 on record is only momentary, and would not conduct current to solenoid coil 56 for a period of time required to operate mechanism engaging with it. The same is true of switch 93, which is only momentarily closed during the revolving of bearing 7, but which trips permanent contact switch at lever 174 to allow continuous current through solenoid 166 until core of same trips this arm 174 and opens the circuit after the full power stroke has been applied.

When it is desired to repeat a record any one of the movable toothed slides 180, as shown in Fig. 14, corresponding to the particular record to be repeated, is drawn out of sliding table 177, the number of notches corresponding to the number of times it is desired that that particular record be repeated. These sliding toothed bars 180 are set manually before the machine is started, to control the number of times any desired record is to be repeated. As bar 170 advances, any of these slides 180 projecting out one or more teeth, enter between springs of electrical spring switch 194; these enter the switch in the order in which the records to be repeated are placed in the carriage and thereby close the circuit at the switch. This allows current to flow to roller contact 91 through spring contact 92 of solenoid coil 86, mounted on bearing 8; when this solenoid due to rotation of bearing 8 comes in contact with spring 92 by means of roller 91. Such contact takes place during the time the steel core 87 passes ratchet stop 99. Referring to Fig. 16, the circuit is completed as follows: Current is taken from bus-bar B at A.A through wire BB to binding post 195 on spring contact switch 194, through toothed slide 180 and out at binding post 196, through wires CC to spring contact 92 where roller 91 on solenoid 86 receives the current leading it into the coil winding when solenoid coil 86 is rotated past the spring contact 92 by bearing 8; this closes the circuit during the time steel core 87 passes ratchet stop 89. By this means no current is allowed to flow through solenoid 86 before or after roller contact 91 comes in contact with spring 92 causing a saving of current if the repeat is set for more than one time; this is necessary, for if roller 91 was in permanent contact with spring 92 the current would flow continuously through solenoid 86 during this entire time causing the winding to heat and waste current. The current flows out of solenoid 86 at DD through wire EE completing circuit with bus-bar A at FF. A suitable number of gummed metal plates 75, as shown in Figs. 10 and 11, will be supplied with each machine for attaching to the various records to be played on the machine. These metal plates 75 will be prepared with a gummed side with one end

cut on a circular arc to conform with the arc of the last tone thread of the average record, and will be applied to the records by moistening the gummed side and applying same across the record label opposite the title in such a manner that the curved end coincides with the last sound groove on the record. The other end is allowed to cover the centering hole in the record. As these plates are of soft metal, a pencil or any suitable stylus can be used to pierce a hole through them corresponding to that in the center of the record. One of these metal plates is applied to both sides of the double disk record and only to the playing side of a single disk record.

It is within the contemplation of my invention to replace solenoids 56 and 166 by small back geared electric motors of conventional type, such as illustrated in Fig. 20, to act as the actuating elements of the apparatus performing the same functions as the solenoids; these motors to be used in cases where the source of electric power consists of special currents of varying cycles and volts which might make operation of the solenoids unsatisfactory.

I prefer to provide in motor 41, as shown in Figs. 1 and 3, an unusually heavy and large diametered armature 203, such as illustrated, which will act as a fly-wheel to steady the rotation of the motor shaft supporting friction wheel 42. Such regulated speed of motor 41 will necessarily impart same regulated speed to turntable which it drives and make reproduction of sound of record more nearly true.

In order to operate the phonograph it is necessary that the record-holding carriages 96 and 125 be expanded to suit the size of the records in the series to be played. The first record to be played is placed on the upper turntable which is in position for playing the record; the second record is placed on the turntable at the left hand side parallel to the record-ejecting carriage 96, and the subsequent records of the series are then placed in the carriage 96 from right to left in the order in which same are to be played. The repeating table 177 is then manually set so as to provide the means for repeating any of the records which are to be played a given number of times. This is done by drawing out the various toothed slides 180 on table 177, the required number of notches corresponding to the number of times the individual records are to be repeated. As it is assumed that under ordinary circumstances there would be no call for more than five repeats of a given record, I have arranged the repeating mechanism for that number. The carriage 177 is then moved to the extreme left so as to bring number one toothed slide opposite the spring switch 194. The switches 199

95

100

110

115

120

125

130

and 200 controlling the turntable motor 41 and the various coil circuits, as above described, are then closed and the reproducer 65 is lowered on the outer edge of the first record, it being revolved by means of the electric motor 41 just started. The operation from this point on is entirely automatic, changing the records in the order of playing and stopping to repeat any of those 10 so desired the number of times predetermined, then continuing on to the next until the series has been exhausted, at which time by means of a conventional time switch the machine is stopped. This time switch can 15 be set to allow for stopping or starting at any predetermined time.

The action of the machine in the proper sequence of the various parts is as follows: When the end of a record is reached by the 20 needle, the contact of metal brush 74 with metal plate 75 on the record closes the circuit through the magnetic switch 58 which in turn controls solenoid 56 causing operations allowing the rotation of turntables and 25 the elevation of the tone arm. This action brings record number two to playing position and places record number one opposite receiving carriage 125, bringing an empty turntable parallel to carriage 96 ready to receive record number three. During the rotation of the turntables switch 93 is closed, causing magnetic switch 171 to complete 30 circuit through solenoid 166. The closing of this circuit causes core 165 to recede 35 within the solenoid 166 and operate the levers which advance and return the carriages simultaneously. (The lower turntable does not carry any records but is used as a reserve disk to receive the records from 40 carriage 96 at the proper time.) As the carriages 96 and 125 advance the next or third record is ejected onto the turntable at the left, and held by means of pin 14; record number one at this time is removed 45 from the turntable at the right. During the receding or return motion of carriages 96 and 125 the advancing racks 99 and 128, acting in groups of three, have passed behind the records and are ready to 50 eject and receive records at the next change. The racks 99 in groups of three move all records ahead on the advancing carriage 96 when the third record is ejected onto the turntable. The racks 128 advance the record number one away from 55 the turntable on the retreat of the carriage 128. The tripping of magnet switch 158 by core 53 causes the reproducer to lower onto the record and the lead screw 60 28 to engage with half nut 72. The releasing of magnet switch 170 by core 165 returns the core to extended position ready for the next advancement of the carriages. Record number two is then played and the 65 operation as described is repeated. This op-

eration continues until all the records in the series have been played.

When a record is to be repeated solenoid 56 alone is operated as the carriages are not required to advance. As the turntables do 70 not revolve during a repeat switch 93 remains open and by so doing leaves solenoid 166 inoperative; this allows for the elevating and lowering of the reproducer 65 but prohibits the revolution of bearing 7 and 75 the turntables. At each lowering of the tone arm any toothed repeating slide extending into the spring switch 194 is reeded into its supporting table 177 until such 80 slide is reeded entirely away from the switch 194. This breaks the contact with solenoid 86 and allows the next record to be placed on the turntable as previously described. Upon each advance motion of the carriage 96 toward the turntables the repeating table 177 is advanced one notch, bringing the toothed slides forward in the order of the records as placed in the carriage so that repetition of any record will 85 be caused should any of these slides be extended to engage with switch 194; if the slides are not extended no contact is made with switch 194 and therefore a change of records will result. The word "turntables" 90 as used in this specification is to be construed as including within its scope any suitable record holding member.

What I claim is:

1. In a phonograph, the combination with 100 a record-rotating carrier, of a record magazine, means for positioning said carrier to receive a record, mechanism for shifting a record from said magazine on said carrier, and means for positioning said carrier for playing.

2. In a phonograph, the combination with 105 a record-rotating carrier, of a record magazine, means for positioning said carrier to receive a record, mechanism for shifting a record from said magazine on said carrier, means for positioning said carrier for playing, and means for taking the record from said carrier.

3. In a phonograph, the combination with 110 a record-rotating carrier having a series of playing tables, of a record magazine, mechanism for taking a record from one of said tables while another record is taken from said magazine and placed on another of said tables, and means for successively positioning said tables for playing.

4. In an automatic electrically controlled phonograph, the combination of means for holding a series of records, a plurality of rotatable turntables on which the records are successively applied, means for automatically applying successive records to the turntables, means for automatically and successively receiving the series of records from the turntables, and means for holding a 115 120 125 130 135

- plurality of turntables in a suitable predetermined position while one of the turntables is rotated for playing the record.
5. In an automatic electrically controlled phonograph, the combination of means for holding a series of records, means for adjusting said holding means to accommodate series of records of different diameters, a plurality of rotatable turntables on which 10 the records are successively applied, means for applying the records successively to the turntables while the turntables are in a predetermined position, means for receiving the series of records from the turntables and 15 holding same, means for adjusting said receiving and holding means to accommodate series of records of different diameters, and means for removing the records from the turntables.
- 20 6. In an automatic electrically operated phonograph having a sound amplifying chamber, the combination of revoluble means extending around the sound amplifying chamber for supporting a plurality of turntables, a plurality of turntables rotatably mounted on said revoluble means, and means for rotating one of the turntables when in playing position.
- 25 7. In an automatic electrically operated phonograph, the combination of revoluble means for supporting a plurality of turntables, the turntable which is uppermost and horizontal being in playing position, means for rotating the turntable which is 30 in playing position, means for successively placing a series of disc records on the turntables, and means for successively removing the disc records from the turntables, said record-removing means being connected to 35 and operated simultaneously with the record-applying means.
- 40 8. In an automatic phonograph, the combination of revoluble means for supporting a plurality of turntables, the turntable which is uppermost and horizontal being in playing position, means for rotating the turntable which is 45 in playing position, means for successively playing a series of disc type records on the turntables, means for revolving the element on which the plurality of turntables are supported at the 50 completion of each playing of a record immediately on the conclusion of the playing, and means for successively removing the disc records from the turntables after they 55 have been played.
- 55 9. In combination with the mechanism described in claim 8, means operatively connected with the turntable supporting mechanism to prevent its normal revolving movement to bring the next turntable into operative position immediately after a record 60 has been played, for permitting of the repeating of any one or more of the series of records for a predetermined number of

times without interfering with the automatic action of the machine in successively playing and removing of the records on and from the turntables.

10. In combination with the apparatus 70 described in claim 8, the combination of means for applying a record to one of the turntables, and other means for simultaneously removing the played record from another of the turntables, and means for adjusting both record shifting means to handle series of records of different diameters. 75

11. In an automatic phonograph, the combination of revoluble means for supporting a plurality of turntables, a plurality of turntables rotatably mounted on said revoluble means, means for holding in operative spaced position a series of disk records to be played, said means being arranged to permit of the removal and replacement of any record or records desired without disturbing other records, means for applying said records to the turntables, means for successively removing records from the turntables after the records have been played, means for holding the series of records that have been played, said means permitting of the removal of any desired record therefrom without disturbing other records. 85

12. In an automatic phonograph, a record holding carriage adapted to hold a series of records to be played and having means to advance said records successively and position them on a turntable, said means comprising a plurality of toothed bars adapted to support the records in spaced relation, a second set of toothed bars arranged to advance the records one tooth at a time in the carriage, resilient means normally holding said bars in contact with the records but permitting of a limited receding movement, the last named bars being arranged to permit of a limited longitudinal movement for advancing the records. 90

13. In combination with the mechanism described in claim 9, manually operated means for relatively moving said tooth bars to adapt the carriage to hold series of disk records of different diameters. 100

14. In an automatic phonograph, the combination of toothed bars adapted to support records in spaced relation, and means adapted to be moved into and out of engagement with the edges of the records to move the records longitudinally of the toothed bars to advance the records toward playing position, substantially as set forth. 105

15. In an automatic phonograph, revoluble means for supporting a plurality of turntables, the turntable which is uppermost and horizontal being in playing position, means for rotating the turntable which is in playing position, means for revolving the revoluble means to bring succeeding turn- 110 115 120 125 130

- tables into playing position, said means comprising an adjacent revoluble member, a solenoid and core mounted on said adjacent revoluble member said core being normally 5 in the path of a projection upon said first named revoluble means, circuit closers adapted to energize said solenoid and withdraw said core from the path of said projection.
- 10 16. In an automatic phonograph, revoluble means for supporting a plurality of turntables, the turntable which is uppermost and horizontal being in playing position, means for rotating the turntable which is 15 in playing position, means for revolving the revoluble means to bring successive turntables into playing position, said means comprising an adjacent revoluble member, a solenoid and core mounted on said adjacent 20 revoluble member, said core being normally in the path of a projection upon said first named revoluble means, a circuit closer adapted to energize said solenoid and withdraw said core from the path of said projection, electrically controlled means for disengaging the aforesaid elements to permit 25 of the repeating of records, and manually adjustable means operatively connected with the revoluble turntable carrying member for 30 setting and controlling the number of times a record is to be repeated before a new record is moved into playing position.
17. In an automatic phonograph, manually adjustable means for setting and controlling the number of times a record is 35 to be repeated, comprising a travelling table having a series of grooves, toothed bars slidably mounted in said grooves, springs holding said bars in adjustable position to 40 control the number of times the record is to be repeated, means for moving the slide- 45 able bars longitudinally in the grooves in the said table a distance of one tooth for each repetition of a record, and means for electrically actuating the aforesaid mechanism.
18. In an automatic phonograph, the combination of a horn throat, an insulated tone arm and base hingedly mounted on 50 and opening into the small end of the horn throat, arms mounted on the hinged base, a carriage rollably mounted on said arms, and a reproducer having an arm integral with its casing member, said arm being 55 pivoted to the carriage element to permit of a sufficient free vertical and horizontal movement of the reproducer to overcome any irregularity in the shape or position of the record on the turntable on which the 60 record is mounted while being played.
19. In an automatic electrically-operated phonograph, the combination of revoluble means supporting a plurality of turntables, the uppermost turntable being in playing 65 position, means for rotating said turntable, a reproducer having a spring metal brush, an electric circuit adapted to be closed by the contact of said metal brush with a suitable electrical conductor attached to the inner portion of the record and extending 70 from the inner end of the grooves of the record to the center of the record, a hinged base and tone arm, a tone tube telescopically mounted in the tone arm, said tone arm carrying a reproducer and the reproducer being thereby returned to its initial position when the tone arm and tone tube are tilted to an inclined position, and electrical means for automatically tilting said tone arm and tone tube to return the reproducer to its initial position for beginning the playing of a record immediately on contact of the metal brush carried by the reproducer with the electrical conductor on the inner portion of the record disc, substantially as and for the purposes described.
20. In an automatic phonograph, the combination of means for holding a series of records, means for advancing and successively applying said records to turntables, rotatable turntables, revoluble means on which the turntables are rotatably mounted, electrically controlled means for intermittently revolving said revoluble means to bring successive turntables into playing position at the appropriate times, means for automatically removing successive records after the records have been played, means for removably holding said series of played records, said record-applying and record-removing means being simultaneously operated, and means for adjusting both said record holding means to accommodate them to series of records of 95 different diameters.
21. In an electrically operated automatic phonograph, reproducing mechanism adapted to be moved into and out of engagement with the record groove of a disc record, electrical means for automatically controlling said reproducing mechanism for moving same into playing position at the beginning of a record groove when a record is brought into playing position on the turntable, said reproducing mechanism including a lead screw having threads corresponding in number with the number of threads per inch on the disc records in general use, a speed regulating gear mechanism in operative engagement with the lead screw, and means for adjusting said mechanism, whereby the speed at which the reproducer travels can be adjusted to correspond with the number of threads on records having a different number of threads per inch and permitting of adjusting the machine for playing a series of records having the tone grooves of some of the records spaced differently from those of others.
22. In an electrically operated automatic 130

phonograph, the combination of revolute means for supporting a plurality of turntables, the uppermost of said turntables being horizontal and in playing position, means for rotating the said turntables, sound-amplifying means extending through and providing a support for the aforesaid revolute means on which the turntables

are mounted to effect a saving in space and allowing the apparatus to be arranged in a smaller cabinet than would otherwise be possible, reproducer mechanism, and electrical means for automatically regulating and resetting the reproducer mechanism, substantially as shown.
